UNITED STATES PATENT OFFICE.

JAROSLAVA BURIAN, OF LEONIA, NEW JERSEY, ASSIGNOR TO THE SEBRING POTTERY COMPANY, OF SEBRING, OHIO, A CORPORATION OF OHIO.

DESIGN FOR A CASSEROLE.

Application filed September 16, 1927. Serial No. 23,433. Term of patent 7 years.

To all whom it may concern:

Be it known that I, JAROSLAVA BURIAN, a citizen of the United States, residing at Leonia, in the county of Bergen and State of New Jersey, have invented a new, original, and ornamental Design for Casseroles, of which the following is a specification, reference being had to the accompanying drawings, forming part hereof.

Fig. 2, a side elevation of the casserole.

I claim:

The ornamental design for a casserole, as shown.

JAROSLAVA BURIAN.
